UNITED STATES PATENT OFFICE.

SOLA B. DUNN, OF CHICAGO, ILLINOIS.

VETERINARY INSTRUMENT.

1,245,325.

Specification of Letters Patent.

Patented Nov. 6, 1917.

Application filed April 11, 1916. Serial No. 90,294.

To all whom it may concern:

Be it known that I, SOLA B. DUNN, a citizen of the United States, residing at Chicago, in the county of Cook and State of Illinois, have invented certain new and useful Improvements in Veterinary Instruments, of which the following is a specification.

This invention relates to veterinary instruments and the purpose is to provide a device adapted for use in relieving a constipated or clogged condition of the alimentary tract, particularly the colon, of a horse or other animal.

10 The principal object of the invention is to provide a device which may be caused to engage the rectum of a horse, for instance, and which may then be manipulated to effect a loosening and discharge of the clogged feces in the colon or other part of the alimentary tract. A further object is to provide an instrument which may be operated in some respects as a syringe for the purpose above indicated. Still another object 25 is to provide an instrument comprising means for introducing a liquid or other loosening medium into the colon of a horse, for instance, in combination with means for sealing up the lower end of the alimentary tract until the liquid has effected a loosening or dissolution of the clogged matter above that point. A further feature is the provision of an apertured member adapted to enter the rectum of an animal and comprising 30 means for introducing a fluid into the colon, in combination with a flexible member which may be inflated to seal or close the rectum below or at the rear of the mouth of said member. Still another feature 35 is the provision of a device of the kind referred to in which the parts may be readily disassembled for inspection, cleaning and repairs. A further object is to provide improved means for securing the device to the animal with which it is used.

These and other objects of the invention will appear more clearly from the following specification taken with the accompanying drawings in which one embodiment of the 40 invention is illustrated.

In the drawings:

Figure 1, is a side elevation of the device showing it in operative relation to a horse, various parts of which are illustrated by 45 dotted lines;

Fig. 2, is a longitudinal sectional view of the device;

Fig. 3, is a rear end elevation of the same; and

Fig. 4, is a sectional view taken on the line 4—4 of Fig. 2.

Referring to the drawings, the plunger or nozzle 10 comprises a body portion 11 which carries at its forward end a head or cap 12. The members 11 and 12 are provided with centrally located alining apertures in which are mounted the tubes or pipes 13 and 14 respectively, the tube 14 of the cap being constructed to project into and form a threaded engagement with the tube 13 of the body 70 member 11. The cap 12 has somewhat the form of a truncated cone, having preferably a slight convexity on its annular surface, whereby it will readily engage the rectum of an animal. An annular flange 11^a is 75 formed on the body portion 11 adjacent the forward end thereof, this flange being spaced from the cap 12 by the reduced portion 11^b which has a square or other suitable non-circular cross section. 80

A diaphragm 15 formed of rubber or other suitable elastic material, is mounted on the reduced portion 11^b of the plunger forming a part of the engaging member. This diaphragm comprises an annular projecting double sheet 15^a and a hub portion 15^b, which fits closely between the flange 11^a and the cap, and which is provided with a suitable aperture adapted to fit closely the surface of the part 11^b, whereby the diaphragm is held in non-rotative engagement with the plunger. A supply tube 16 of preferably rubber or the like leads to the diaphragm 15 through the flange 11^a which is preferably of slightly greater diameter 90 than the largest part of the cap. This tube 16 is preferably embedded in a groove formed in and extending longitudinally of the body member 11. The parts 11 and 12 are preferably formed of hard wood, although other suitable materials may be used if desired. 95

At its rear end the body member 11 carries an arcuate flange 11^c on its under side. Secured to this flange by screws 17 is a 105 plate 18 having an outwardly directed arcuate flange 18^a around its lower and lateral edges. The tube 16 leads through this plate and the pipe 13 also projects therethrough to engage the valve 19 having a serrated 110

mouth portion 19^a adapted to be connected to a suitable source of water or other liquid supply. The tube 16 is adapted to be connected to a supply of compressed air or the like and a stop cock 20 is located therein for controlling said supply.

For the purpose of securing the device in position, the flange 18^a of the plate 18 is provided at its lowermost portion and on its lateral sides with slots 21 which are engaged by the straps 22 which are secured to the plate. The position of the device engaging the rectum of a horse 23 is shown in Fig. 1, where the horse is illustrated by dotted lines. The lower strap 22 passes downwardly between the legs of the horse and the other straps pass around the haunches of the horse and forwardly at its sides.

All of the straps are secured to the surcingle 24 which passes around the body of the horse. Buckles are provided to permit detachment and adjustability of the straps. A shoulder strap 25 is connected to the rings 24^a of the surcingle thus preventing rearward displacement of the harness and other parts of the apparatus.

In the operation of the instrument the nozzle or plunger 10 is caused to engage the rectum of the horse, as illustrated in Fig. 1 for instance, and the straps 22 are then connected to the surcingle or other support whereby the device is held in relatively fixed position with respect to the animal. The tubes 13 and 16 are connected to supplies of water and compressed air, respectively, with the cocks 19 and 20 closed. The cock 20 is then opened, permitting the compressed fluid to inflate the diaphragm 15, as shown in Fig. 1 and as represented by dotted lines in Fig. 2, and thereby sealing or closing up the rectum 23^a of the horse. The cock 19 is then opened and the liquid forced through the duct of the plunger into the intestinal tract in front of the diaphragm which serves to prevent the escape of the liquid, until it has been retained in the intestines a sufficient length of time to effect a loosening or softening of the clogged matter therein. After the desired quantity of liquid has

been introduced through the plunger, the cock 19 may be closed and the liquid permitted to remain in the intestinal tract a suitable period of time, after which the diaphragm is deflated and the instrument removed. It will then be observed that the diaphragm when deflated will fold over the cap 12 or the flange 11^a according to the direction of movement of the device and that the parts of the device are so shaped as to permit the ready insertion and withdrawal of the plunger. The diaphragm has a non-rotative engagement with the plunger thereby preventing relative movement of those members which might sever the connection of the diaphragm with the tube leading thereto. When it is desired to clean or repair the various parts, the cap 12 may be disengaged from the body portion and the diaphragm withdrawn.

Although the construction and operation of the apparatus have been particularly described for purposes of illustration, it will be understood that it may be embodied in various forms without departing from the scope of the invention as defined in the appended claims.

I claim:

In a device of the class described, the combination with a plunger having a passageway extending longitudinally therethrough, said plunger having a radially reduced portion forming shoulders on opposite sides thereof, of an annular inflatable diaphragm radially surrounding said plunger and fitting closely around said reduced portion thereof, whereby said shoulders prevent movement of said diaphragm longitudinally on said plunger, said reduced portion of the plunger being angular in cross section and the opening of said diaphragm conforming to such angular cross section, and a conduit secured to said plunger and connected with said diaphragm for supplying an inflating fluid thereto.

In testimony whereof, I have subscribed my name.

SOLA B. DUNN.
